CLAIM

(51) **LOC (14) Cl.** **14-02**

The ornamental design for a joystick for utility vehicle, as shown and described.

(52) **U.S. Cl.**

DESCRIPTION

USPC **D14/413**

(58) **Field of Classification Search**

USPC D13/167, 168; D14/412, 413, 414, 415; D21/324, 320, 333, 566

CPC G08C 17/00; G06F 3/03549; G05G 9/047

See application file for complete search history.

(56) **References Cited**

FIG. 1 is a front left perspective view of a first embodiment of a joystick for utility vehicle according to my new design; FIG. 2 is a bottom plan view thereof; FIG. 3 is a top plan view thereof; FIG. 4 is a left side elevational view thereof; FIG. 5 is a right side elevational view thereof; FIG. 6 is a front elevational view thereof; and, FIG. 7 is a bottom rear perspective view thereof. The broken lines in the views show portions of the joystick for utility vehicle that form no part of the claimed design.
